RAILWAY SIGNAL.

No. 380,316.

Patented Apr. 3, 1888.

UNITED STATES PATENT OFFICE.

J. HAMILTON FARRAR, OF CHICAGO, ILLINOIS.

RAILWAY-SIGNAL.

SPECIFICATION forming part of Letters Patent No. 380,316, dated April 3, 1883.

Application filed July 23, 1887. Serial No. 245,111. (No model.)

To all whom it may concern:

Be it known that I, J. HAMILTON FARRAR, a citizen of the United States, residing at Chicago, in the county of Cook and State of Illinois, have invented new and useful Improvements in Electric Railway-Signals, of which the following is a specification.

The present invention relates to that class of railway signaling apparatus in which electro-mechanical signaling devices are included in an electric circuit formed by sections of the railway-track or wire conductors.

The invention has for its object to provide simple and effective devices constituting a vibratory signal, which is maintained in a constant state of activity to indicate a clear track, and is only stopped when, by the passage or action of a train, the electric circuit in which the signal is included is broken.

20 In the accompanying drawings, Figure 1 is a perspective view showing a vibratory signal, a railway-track, and means for operating the signal. Fig. 2 is a view of an automatic circuit-breaker with signal-disk on its armature. 25 Fig. 3 is a detail view of a lantern-box and vibratory signal-arm.

The reference-numerals 1 and 2 indicate the rails of a railway-track which, in the present instance, is divided into sections of a mile 30 (more or less) in length, by properly insulating the joints between each section and metallically connecting the rails of each section. Each section of a railway-track thus divided or insulated from an adjoining section constitutes part of an electric circuit, in which is included a signaling apparatus of the following 35 description: An electro-magnet, 3, is connected by a wire, 4, with one of the rails, and from the other rail extends a wire, 5, which 40 goes to a binding post or pin, 6, on a metal post, 7, of the frame on which the electro-magnet is mounted. An armature, 8, pivoted to the frame, faces the pole of the electro-magnet, and is extended to form a long lever, 9, carrying 45 a visual signal-disk, 11, at its outer end.

A spiral or other spring, 10, connected with the post 7 and armature-lever, exerts a pull upon the latter and retracts it against the pin 6. A galvanic battery, 12, connected with the 50 track-rails or circuit-wires, is the source of electricity for energizing the electro-magnet

and attracting the armature or signal lever. This lever operates in precisely the same manner as the armature of a rheotome or automatic circuit-breaker; or, in other words, it 55 vibrates rapidly between the pole of the electro-magnet and the pin 6, and in consequence thereof the semaphore-disk carried by the lever is correspondingly vibrated. It is the intention to have the signal in constant vibration 60 in order to indicate "safety" or a clear track. When, however, a train passes upon the track or section in which the signal is located, the electric current is diverted through the wheels and axle of the car and the signal comes to 65 rest in order to indicate "danger." The signal shown in Figs. 1 and 2 is adapted for day use, and in the form shown in Fig. 3 the signal-disk operates within a casing, 15, which encloses a lamp, 16, and has an opening, 17, for 70 the passage of light. The signal-disk, by covering and uncovering this opening, causes flashes of light to be emitted in rapid succession through the opening in the box.

It will be understood from the foregoing description that I provide means for rapidly vibrating a lever carrying a signal-disk, and that such operation is performed automatically.

While I have shown the signal as being adapted to a system in which insulated track-sections constitute part of an electric circuit, it is evident that without departing from my invention I can use circuit-wires and control the movement of the vibratory signal by a manual or automatic switch. In Fig. 2 I have 85 shown what may be considered a wire circuit, which contains a manual switch, 15, which is under the control of the track attendant. My signal, in addition to the uses already described, will serve to indicate the presence of 90 broken rails, open draw-bridges, and other dangerous and abnormal conditions of a railway-track.

Having thus described my invention, what I claim is—

1. A railway signaling apparatus, consisting of an electric circuit, a rheotome having a lever-armature, and a visual signal mounted on the latter, substantially as described.

2. In a railway signaling apparatus, an electric circuit in which a section of the track is included, a rheotome lying in said circuit, a

vibrating armature carrying a visual signal, and a spring drawing said armature away from the pole of the rheotome, substantially as described.

5 3. In a railway signaling apparatus, an electric circuit in which a section of the track is included, a rheotome lying in said circuit, an armature carrying a signal-disk, a spring

drawing said armature away from the pole of the rheotome, and a lamp-box having an opening over which the signal-disk vibrates, substantially as described.

J. HAMILTON FARRAR.
